MATCH PACKAGE

Ralph Kenneth Newton and Irwin Carl Prafke,
Madison, Wis.

Application May 5, 1939, Serial No. 271,994

3 Claims. (Cl. 206—48)

This invention relates to a match package, and more particularly to a match package designed for use in association with the conventional package of cigarettes.

5 It is an object of this invention to provide a match package equipped with means for locking it to a cigarette package in such a manner as to insure its permanent association with the cigarette package thereby affording a convenient assembly of cigarettes and matches.

10 It is a further object of this invention to provide a match package so constructed as to render the matches readily accessible after the match package has been attached to a cigarette package.

15 An additional object is to provide a match package, which, after attachment to the cigarette package, furnishes a closure for the opened end of the cigarette package through which the cigarettes pass on removal.

20 Still another object is to provide a match package, which, after attachment to the top of a cigarette package, furnishes a reinforcement for the top of the cigarette package thereby affording a more sturdy package and resulting in the consequent preservation of the original shape of the cigarettes contained therein.

25 Other objects and advantages will be readily apparent from the following detailed description when read in connection with the accompanying drawing forming a part hereof, and wherein the preferred embodiment of our invention is illustrated.

In said drawing:

30 Figure 1 is a plan view of the match package in open position.

Figure 2 is a top end view of a conventional cigarette package showing the manner of insertion with the locking portion of the match package between the folds of the cigarette package.

35 Figure 3 is a plan view, portions being broken away, with one of the top folds of the cigarette package open to show the engagement of the locking portion of the match package therewith.

40 Figure 4 is a perspective view showing the opposite folds of the cigarette package open and the manner of inserting, and the position of the locking portion of the match package over the end fold of the cigarette package.

45 Figure 5 is a vertical sectional view of the cigarette package showing the match package applied thereto and in the closed position of the latter.

50 Figure 6 is a side view of the upper portion of the cigarette package with the match package applied and held thereto, parts being shown in

section, and the match package in open position with the match package disposed and resting against the edge of the cigarette package.

5 Figures 7 and 8 are plan views, on a reduced scale, of modified formations of the locking portion of the match package.

Referring more specifically to the drawing:

The match package is illustrated in open position in Figure 1 wherein numeral 1 indicates the locking portion, 2 is the back portion, said parts 10 1 and 2 forming a relatively long cover flap, and 3 is the upwardly folded front portion, or relatively short cover flap, the latter extending to a point adjacent the heads of the contained matches; 4 is a bank of matches, 5 is a staple which fastens the match bank within the match package in customary fashion, and 6 is an abrasive which is applied to the package in the usual way. Notches 7 are formed in the locking portion 1 which provide pointed prongs, shoulders, or barbs 8, the latter being adapted to engage the inner end edges of the customary top folds 9 of a cigarette package 11 thereby holding the match package in locked relation with respect to the cigarette package. 12 is a binding strip which extends, as usual, 20 across the top of the cigarette package and holds the top folds 9 and the end folds 10 in their folded position. Numerals 13 and 14 represent scoring lines upon which the cover strip of the match package is folded and unfolded when the match package assumes a closed or opened position.

In order to attach the match package to a package of cigarettes, while rendering the cigarettes accessible for removal, one end portion of the top of the cigarette package will be removed by tearing along dotted lines 15 (Figure 2) in the usual manner to leave a correspondingly unobstructed area through which cigarettes, as desired, may be withdrawn; then the locking portion 1 of the match package is inserted at the un-

35 torn end portion of the cigarette package beneath the top folds 9 and above end fold 10 until barbs 8 pass beyond the inner end edges of folds 9 and 10; finger pressure is then brought to bear on the sides of the cigarette package at the top center thereof, and at the same time, locking portion 1 is slowly retracted thereby causing barbs 8 to engage the inner end edges of the top folds 9, as shown in Figures 3 and 4, thus locking the match package on the cigarette package. The 40 match carrying portion 2 is then swung over on top of the cigarette package, front portion 3 being inserted between locking portion 1 and the folded over sides of the cigarette package as 45 shown in Figure 5. These folded over sides are, 50 55

as usual, continuations of the top folds 9 previously referred to.

It will be understood that the wrapping for the package of cigarettes is of conventional form, 5 preferably of paper faced on the exterior with tinfoil, and that in formation the end folds 10 are first folded down upon the ends of the enclosed cigarettes with the top folds 9, which are of course integral with the material of the end folds 10, then folded downwardly upon the end folds 10 in overlapping relationship, to be held in position, as stated, by the binding strip 12. The tinfoil facing of the folds 9 and 10 provide smooth faces and also smooth junctures at the creases 15 between the folds 9 and 10 to facilitate the introduction of the locking portion 1 of the match package and the shifting of said locking portion to inserted and to partially retracted position between the folds 9 and 10.

20 It will be noted that when our match package is attached to a cigarette package, it not only affords a convenient assembly of cigarettes and matches, but it also acts as a closure for the opened end portion of the cigarette package, thus 25 serving to prevent the accidental displacement of cigarettes from the package as well as the escape of tobacco from the cigarettes at the opened end of the package into the pocket, pocketbook, or the like of the user. It will also be noted that 30 the match package including its cover flaps is of substantially the same width as the cigarette package.

When the user desires to gain access to the cigarettes and matches, he merely grasps the bottom or stapled end of the match package, and, by pulling outwardly and upwardly, front portion or flap 3 will be released from the cigarette package, after which the match carrying portion may be swung over assuming a position parallel to 40 and along the side of the cigarette package as shown in Figure 6.

Figures 7 and 8 are detail views on a reduced scale of modified forms of the locking portion 1. In Figure 7, the free end 16 of the locking portion 45 1 is shown as of rounded formation, whereas in Figure 8, free end 17 is shown to be of somewhat tapered or relatively pointed formation. The purpose of both modifications is to facilitate the insertion of the locking portion 1 between folds 50 9 and 10 of the cigarette package when the match package is applied thereto.

It will be understood that minor changes in the form, structure, and combination of the various parts of our improved package may be resorted to without departing from the spirit of our invention as defined in the hereto appended claims; for example, it is appreciated that in instances, the barbs 8 being of sufficiently rigid material and sharp, the match package may be 55 caused to firmly hold itself to the cigarette package by simply pressing the tinfoil or paper wrapper into impingement on the barbs.

We claim:

1. An attachment for a conventional cigarette package possessing a closed top providing end 60 openings; said attachment consisting of a match package having a bank of matches and relatively

long and relatively short cover flaps on opposite sides of said match bank, the width of said package including the flaps being substantially the same as the width of the conventional cigarette package, the relatively short cover flap extending to a point adjacent the match heads and the relatively long cover flap adapted to extend around the heads of the matches and overlap said short flap substantially throughout, the overlapping portion of said long flap having an integral barb 10 on a longitudinal edge projecting rearwardly thereof formed by an undercut notch therein and said long flap being adapted to be inserted through one end opening of the cigarette package, the said barb acting to secure the long flap therein, and said short flap being adapted to be inserted through the opposite end opening of the cigarette package.

2. An attachment for a conventional cigarette package possessing a closed top providing end 20 openings; said attachment consisting of a match package having a bank of matches and relatively long and relatively short cover flaps on opposite sides of said match bank, the width of said package including the flaps being substantially the same as the width of the conventional cigarette package, the relatively short cover flap extending to a point adjacent the match heads and the relatively long cover flap adapted to extend around the heads of the matches and overlap said short 25 flap substantially throughout, the overlapping portion of said long flap having an integral barb on each of its longitudinal edges formed by opposed notches therein and said long flap being adapted to be inserted through one end opening 30 of the cigarette package, the said barbs acting to secure the long flap therein, and said short flap being adapted to be inserted through the opposite end opening of the cigarette package.

3. The combination of a cigarette and match 40 package, said cigarette package possessing a closed top including end and top folds providing end openings and said match package having a bank of matches and relatively long and relatively short cover flaps on opposite sides of said match bank, the width of said package including the flaps being substantially the same as the width of the cigarette package, the relatively short cover flap extending to a point adjacent the match heads and the relatively long cover flap 45 extending around the heads of the matches and overlapping said short flap substantially throughout, the overlapping portion of said long flap having an integral barb on each of its longitudinal edges formed by opposed notches therein, said 50 match package being attached to said cigarette package by inserting said long flap through one end opening of the cigarette package, said barbs engaging with edge portions of the top folds of the cigarette package to prevent separation of 55 the match package therefrom, and said short flap being inserted through the opposite end opening of the cigarette package and removably confined between said closed top and said long flap.

RALPH KENNETH NEWTON.
